PRESSURE FLUID MOTOR

Filed Nov. 1, 1934

UNITED STATES PATENT OFFICE

2,100,325

PRESSURE FLUID MOTOR

Elmer G. Gartin, Claremont, N. H., assignor to
 Sullivan Machinery Company, a corporation of
 Massachusetts

Application November 1, 1934, Serial No. 751,012

25 Claims. (Cl. 121—26)

This invention relates to pressure fluid motors, and more particularly has reference to improvements in the fluid distribution means of a pressure fluid motor of the reciprocating piston type.

5 An object of this invention is to provide an improved pressure fluid motor. Another object is to provide an improved pressure fluid motor having improved fluid distribution means. Yet another object is to provide an improved fluid 10 distribution means having an improved valve mechanism whereby the flow of pressure fluid to and the exhaust of fluid from the motor cylinder is controlled in improved and more effective manner. A further object is to provide an improved fluid 15 distributing valve having improved flow passage means and an improved arrangement of passages controlled thereby. These and other objects of the invention will, however, herein-after more fully appear in the course of the following description and as more particularly pointed out in the appended claims.

In the accompanying drawing there is shown for purposes of illustration one form which the invention may assume in practice.

25 In this drawing,—

Fig. 1 is a longitudinal sectional view taken through the illustrative form of the improved pressure fluid motor.

Fig. 2 is a view similar to Fig. 1 showing the 30 moving motor parts in a different position.

Fig. 3 is a cross sectional view taken on line 3—3 of Fig. 2.

Fig. 4 is a cross sectional view taken on line 4—4 of Fig. 1.

35 Fig. 5 is a cross sectional view taken on line 5—5 of Fig. 1.

Fig. 6 is a side elevational view of the improved fluid distributing valve.

Fig. 7 is an end elevational view of the distributing valve.

40 In this illustrative embodiment of the invention there is shown an improved pressure fluid motor of the reciprocating piston type comprising a cylinder 1 having a bore 2 containing a reciprocating motor piston 3. This piston has a head 4 fitting the bore 2 and an integral forwardly projecting bar portion 5 slidably guided in a bore 6 in the front motor head 7. Formed within the rearward portion of the motor cylinder 45 in alignment with the cylinder bore is an enlarged bore 8, and arranged in this bore and abutting a shoulder 9 surrounding the rear end of the cylinder bore is a valve chest member 10, while likewise arranged in the bore 8 and engaging and holding the valve chest member 10

in position against the shoulder 9 is a member 11 having a forward guide projection 12. The member 11 has a central bore 13 through which extends a rod-like member 14, and this member projects in a suitable manner within the motor piston which is made hollow to receive this rod portion. The parts 7, 10 and 11 are held in assembled relation with respect to the motor cylinder in any appropriate manner. The member 14 is herein a portion of the rotation means for 10 the drill.

Now referring to the improved fluid distribution means, it will be noted that formed in the valve chest member 10 is a valve chamber 15 having arranged therein an automatic fluid actuated fluid distributing valve 16 of an improved design, this valve being guided for reciprocatory movement in the valve chamber on the guide projection 12, as hereinafter more fully pointed out. The valve chamber 15 is formed with stepped 20 bores, an enlarged bore 17 and a reduced bore 18, and the fluid distributing valve, which is herein of the sleeve type, has a sleeve-like body 19 fitting the smaller bore 18 and formed at its rearward end with an enlarged flange or spool 20 fitting the enlarged bore 17, and the inside 21 of this valve is slidably guided on the exterior periphery of the cylindrical portion 22 of the guide projection 12. This guide projection has a shoulder 23 with which the rear end of the 30 distributing valve is engageable for limiting rearward motion of the valve, while the front wall of the enlarged bore 17 provides a shoulder 24 with which the forward surface of the flange 20 is engageable for limiting forward motion of the 35 valve. Formed in the valve chest member 10 adjacent the forward end thereof is an internal annular groove 25 to which pressure fluid is supplied through a series of longitudinal passages 26 communicating with any suitable pressure fluid 40 source. Also formed internally within the valve chest member is an annular groove 27 arranged adjacent the flange 20 of the valve and connected through a series of passages 28 to exhaust, while arranged in the member 10 between the grooves 45 25 and 27 is an annular groove 29 connected by a passage 30 and port 31 with the forward end of the cylinder bore. The forward end of the valve chamber is connected directly with the rear end of the cylinder bore through a large axial 50 passage 32 herein of the same diameter as the reduced bore 18 of the valve chamber. As above pointed out, the fluid distributing valve is of an improved design, and has formed externally on the periphery of the sleeve-like body portion 19 55

an annular groove 33, while the front end of the sleeve-like body portion of the valve is provided with an inwardly directed annular flange 34, while the guide projection 12 is provided at 5 its forward end with an external flange 35 adapted to cooperate with the flange 34, as hereinafter pointed out. Formed externally on the guide projection 12 adjacent the flange 35 is an annular groove 36, while formed centrally within the guide 10 projection is an enlarged bore 37 connected at its rear end with the valve chamber through a radial passage 38. The sleeve-like portion 19 of the valve is perforated by a series of radial ports 39, while the enlarged flange 20 of the valve is 15 perforated by a radial port 40. Also traversing the valve body and connecting an interior groove 41 within the valve with the external groove 33 is a series of radial ports 42. The motor cylinder is provided with a central, piston controlled, 20 free exhaust port 44, while communicating with the cylinder bore through a port 45 and controlled by the piston is a valve throwing passage 46 communicating with an annular recess 47 formed in the member 11 at the rear of the valve. 25 When the parts are in the position shown in Fig. 1, pressure fluid may flow through the supply passages 26, annular groove 25, through the valve chamber past the forward surface of the valve body and through the axial passage 32 to 30 the rear end of the cylinder bore, the pressure fluid acting on the rear pressure area of the motor piston to drive the latter forwardly. At this time the forward end of the cylinder bore is connected to exhaust through the central exhaust 35 port 44 and through port 31, passage 30, groove 29, groove 33, groove 27 and exhaust passages 28. It will be noted that the pressure fluid flowing from the supply groove 25 through the axial 40 passage 32 to the rear end of the cylinder bore flows not only from the groove 25 past the forward peripheral edge of the valve, but also flows through the series of radial ports 39 through groove 36 and through the space between the flanges 34 and 35, there being provided by this 45 double flow a large flow area with slight valve movement. As the motor piston moves forwardly, the piston head closes the free exhaust port 44, and as the rear edge of the piston head overruns the port 45 pressure fluid is supplied from 50 the rear end of the cylinder bore through the throw passage 46 to the recess 47 at the rear of the valve, the pressure fluid in this recess acting on the rear pressure area of the enlarged valve flange 20 aided by the pressure acting on 55 the differential pressure area at the rearward side of the valve flange 34 to throw the valve forwardly from the position shown in Fig. 1 to the position shown in Fig. 2. This action, if not completed prior to the uncovering of port 44 by 60 the rear face of the piston, would be augmented by the lowering of the pressure on the forward face of 19. When said valve is in its front position the sleeve-like body of the valve enters the axial passage 32 to cut off communication 65 of the valve chamber with the rear end of the cylinder bore, the internal flange 34 on the valve cooperating at that time with the flange 35 to cut off the groove 36 from the passage 32. The valve is held in this forward position by the pressure 70 acting on the rearward surface of the valve flange 34. Upon forward movement of the motor piston slightly beyond the point of uncovering 45, it will be noted that the rear edge of the piston head overruns the exhaust port 44, thereby con-

necting the rear end of the cylinder bore to exhaust.

When the parts are in the position shown in Fig. 2, pressure fluid flows through the supply passages 26, annular groove 25, through the 5 groove 33, groove 29, passage 30 and port 31 to the forward end of the cylinder bore. The pressure fluid flows not only past the exterior surface of the valve, but also flows through the series of radial ports 39, groove 36, through groove 41, 10 the series of radial ports 42 and groove 33 to the groove 29, there being provided a double flow past the exterior and interior surfaces of the valve body, this double flow providing free flow of pressure fluid with slight valve movement. 15 At this time the rear end of the cylinder bore is further connected to exhaust through the bore 31, passage 38, passage 40 in the valve, groove 27 and exhaust passage 28. At this same time the pressure in the recess 47 at the rear of the valve 20 is connected to exhaust through passages 46, 45 and free exhaust port 44. The pressure fluid flowing through passage 30 and port 31 to the forward end of the cylinder bore acts on the forward pressure area of the motor piston to 25 drive the latter rearwardly. As the motor piston moves rearwardly the forward edge of the piston head overruns the free exhaust port 44, thereby connecting the forward end of the cylinder bore to exhaust, and as rearward movement of the 30 motor piston continues, the pressure fluid largely trapped within the rear end of the cylinder bore is compressed, this compression pressure acting on the front pressure area of the valve body to throw the valve rearwardly from the position 35 shown in Fig. 2 to the position shown in Fig. 1. This result is delayed, and high speed of rearward movement promoted, by the venting through 37, 38, 40, 27 and 28. When again thrown rearwardly the valve 16 is held in its 40 rearward position by the pressure fluid flowing past the forward pressure area of the valve body. In regard to the forward throwing movement of the valve, it will be noted that as the pressure fluid flows from the groove 25 through the axial 45 passage 32 to the rear end of the cylinder bore, the pressure acting on the rear pressure area of the valve flange 34 is substantially higher, due to fluid flow, than the pressure at the forward side of the valve flange 34 so that when the valve 50 is thrown forwardly the pressure acting on the rear pressure area of the flange 34 aids materially the pressure fluid acting on the rear pressure area of the valve. It will also be observed that although the valve has a very slight throwing 55 movement, an ample flow area is provided due to the double flow past the external and internal surfaces of the valve. It will also be evident that by the provision of the auxiliary exhaust means supplementing the free exhaust port 44 an un- 60 impeded exhaust flow from the motor cylinder is promoted. In the position of the valve during the blow striking passes of the piston, auxiliary exhaust through 28 also is provided. Other uses and advantages of the improved pressure fluid 65 motor will be clearly apparent to those skilled in the art.

While there is in this application specifically described one form which the invention may assume in practice, it will be understood that this 70 form of the same is shown for purposes of illustration and that the invention may be modified and embodied in various other forms without departing from its spirit or the scope of the appended claims.

What I claim as new and desire to secure by Letters Patent is:

1. In a pressure fluid motor, a cylinder having a bore, a piston reciprocable therein, and fluid distribution means for effecting reciprocation of said piston including a valve chest having a valve chamber, a fluid actuated fluid distributing valve movably mounted in said valve chamber, and passage means controlled by the valve for supplying pressure fluid to the opposite ends of the cylinder bore and including passage means in said valve for providing a double fluid flow past the external and internal surfaces of the valve to the opposite ends of the cylinder bore.
  2. In a pressure fluid motor, a cylinder having a bore, a piston reciprocable therein, and fluid distribution means for effecting reciprocation of said piston including a valve chest having a valve chamber, a fluid actuated fluid distributing valve movably mounted in said valve chamber, and passage means controlled by the valve for supplying pressure fluid to the opposite ends of the cylinder bore and including passage means in said valve for connecting the exterior 25 of the valve with the interior thereof to provide a double fluid flow past the external and internal surfaces of the valve to the opposite ends of the cylinder bore, said passage means in said valve providing double flow of pressure fluid from the exterior of the valve past the external and internal surfaces of the valve when said valve is in its position to supply pressure fluid to the front end of the cylinder bore or its position to supply pressure fluid to the rear end of the cylinder bore.
  3. In a pressure fluid motor, a cylinder having a bore, a piston reciprocable therein, and fluid distribution means for effecting reciprocation of said piston including a member providing a valve chamber having enlarged and reduced bores, a fluid actuated fluid distributing valve of the sleeve type reciprocable in said valve chamber and having an enlarged flange fitting the larger bore and a sleeve-like body portion fitting the smaller bore, and passage means controlled by said valve for supplying pressure fluid to the opposite ends of the cylinder bore, the sleeve-like portion of the valve body being traversed by a series of radial passages through which pressure fluid flows to the opposite ends of the cylinder bore.
  4. In a pressure fluid motor, a cylinder having a bore, a piston reciprocable therein, and fluid distribution means for effecting reciprocation of said piston including a member providing a valve chamber having enlarged and reduced bores, a fluid actuated fluid distributing valve of the sleeve type reciprocable in said valve chamber and having an enlarged flange fitting the larger bore and a sleeve-like body portion fitting the smaller bore, and passage means controlled by said valve for supplying pressure fluid to the opposite ends of the cylinder bore, the sleeve-like portion of the valve body being traversed by a series of radial passages through which pressure fluid flows to the opposite ends of the cylinder bore, said valve being provided with passage means including said series of radial passages for obtaining double flow of pressure fluid past the external and internal surfaces of the sleeve-like body portion of the valve.
  5. In a pressure fluid motor, a cylinder having a bore, a piston reciprocable therein, and fluid distribution means for effecting reciprocation of said piston including a member providing a valve chamber having enlarged and reduced bores, a fluid actuated fluid distributing valve of the sleeve type reciprocable in said valve chamber and having a rear pressure area, said valve formed at its 75
- a valve chamber having enlarged and reduced bores, a fluid actuated fluid distributing valve of the sleeve type reciprocable in said valve chamber and having an enlarged flange fitting the larger bore and a sleeve-like body portion fitting the smaller bore, passage means controlled by said valve for supplying pressure fluid to the opposite ends of the cylinder bore, the sleeve-like portion of the valve body being traversed by a series of radial passages through which pressure fluid flows to the opposite ends of the cylinder bore, said valve being provided with passage means including said series of radial passages for obtaining double flow of pressure fluid past the external and internal surfaces of the sleeve-like body portion of the valve, and passage means controlled by the valve for connecting the opposite ends of the cylinder bore to exhaust.
6. In a pressure fluid motor, a cylinder having a bore, a piston reciprocable therein, and fluid distribution means for effecting reciprocation of said piston including a member providing a valve chamber having enlarged and reduced bores, a fluid actuated fluid distributing valve of the sleeve type reciprocable in said valve chamber and having a rear annular flange fitting the larger bore and a sleeve-like body portion fitting the smaller bore, the forward end of the valve chamber communicating directly with the rear end of the cylinder bore through a large axial passage, a passage communicating with the valve chamber for connecting the valve chamber with the forward end of the cylinder bore, a fluid supply source communicating with the valve chamber, said valve in its different positions controlling the flow of pressure fluid from said fluid supply source through said passages to the opposite ends of the cylinder bore, said valve being traversed by passage means through which pressure fluid flows through said passages to the opposite ends of said cylinder bore.
7. In a pressure fluid motor, a cylinder having a bore, a piston reciprocable therein, and fluid distribution means for effecting reciprocation of said piston including a member providing a valve chamber having enlarged and reduced bores, a fluid actuated fluid distributing valve of the sleeve type reciprocable in said valve chamber and having a rear annular flange fitting the larger bore and a sleeve-like body portion fitting the smaller bore, the forward end of the valve chamber communicating directly with the rear end of the cylinder bore through a large axial passage, a passage communicating with the valve chamber for connecting the valve chamber with the forward end of the cylinder bore, a fluid supply source communicating with the valve chamber, said valve in its different positions controlling the flow of pressure fluid from said fluid supply source through said passages to the opposite ends of the cylinder bore, said valve being traversed by passage means through which pressure fluid flows through said passages to the opposite ends of said cylinder bore, and passage means including a passage formed in said valve for venting the opposite ends of the cylinder bore to atmosphere.
8. In a pressure fluid motor, a cylinder having a bore, a piston reciprocable therein, and fluid distribution means for effecting reciprocation of said piston including a member providing a valve chamber having enlarged and reduced bores, a fluid actuated fluid distributing valve of the sleeve type reciprocable in said valve chamber and having a rear pressure area, said valve formed at its 75

- rear end with an enlarged radial flange fitting the larger bore and a forwardly projecting sleeve-like body portion fitting the smaller bore, said valve having formed internally thereon at its forward end an annular flange and adjacent said end traversed by a series of radial passages, and passage means controlled by said valve for supplying pressure fluid to the opposite ends of the cylinder bore, the pressure fluid flowing through said series of radial passages to said passage means in either position of said valve, and means for throwing said valve embodying means for supplying pressure fluid to the rear pressure area of the valve and to the rear pressure area of the front internal valve flange, said valve being thrown in one direction by pressure fluid acting on the rear pressure area of the valve aided by the pressure fluid acting on the rear pressure area of the front internal valve flange.
- 20 9. In a pressure fluid motor, a cylinder having a bore, a piston reciprocable therein, and fluid distribution means for effecting reciprocation of said piston including a member providing a valve chamber having enlarged and reduced bores, a fluid actuated fluid distributing valve of the sleeve type reciprocable in said valve chamber and having a rear pressure area, said valve formed at its rear end with an enlarged radial flange fitting the larger bore and a forwardly projecting sleeve-like body portion fitting the smaller bore, said valve having formed internally thereon at its forward end an annular flange and adjacent said end traversed by a series of radial passages, and passage means controlled by said valve for supplying pressure fluid to the opposite ends of the cylinder bore, the pressure fluid flowing through said series of radial passages to said passage means in either position of said valve, and means for throwing said valve embodying means for supplying pressure fluid to the rear pressure area of the valve and to the rear pressure area of the front internal valve flange, said valve being thrown in one direction by pressure fluid acting on the rear pressure area of the valve aided by the pressure fluid acting on the rear pressure area of the front internal valve flange and the valve being thrown in the opposite direction by compression pressure acting on the front pressure area of the valve body.
- 40 10. In a pressure fluid motor, a cylinder having a bore, a piston reciprocable therein, and fluid distribution means for effecting reciprocation of said piston including a valve chest having a valve chamber, a fluid actuated fluid distributing valve of the sleeve type reciprocable in said valve chamber, said valve having a rearwardly located enlarged external flange and a forwardly projecting sleeve-like body portion, a groove formed externally on the sleeve-like body portion, a groove formed internally within the valve body portion, a series of radial ports in the valve body traversing the valve body for connecting the internal groove with the external groove, an internal flange on the front end of the valve body, a second series of radial ports traversing the valve body adjacent to and at the rear of said internal flange, passage means controlled by the valve for supplying pressure fluid to the opposite ends of the cylinder, the pressure fluid flowing through said last named series of radial ports, through said internal groove, said first named series of radial ports and said external groove to one end of the cylinder and through said last named series of radial ports and past said internal flange to the opposite end of the cylinder.
- 60 12. In a pressure fluid motor, a cylinder having a bore, a piston reciprocable therein, and fluid distribution means for effecting reciprocation of said piston including a valve chest having a valve chamber, a fluid actuated fluid distributing valve of the sleeve type reciprocable in said valve chamber and having a rear pressure area, said valve having a rearwardly located enlarged external flange and a forwardly projecting sleeve-like body portion, a groove formed externally on the sleeve-like body portion, a groove formed internally within the valve body portion, a series of radial ports in the valve body traversing the valve body for connecting the internal groove with the external groove, an internal flange on the front end of the valve body, a second series of radial ports traversing the valve body adjacent to and at the rear of said internal flange, passage means controlled by the valve for supplying pressure fluid to the opposite ends of the cylinder, the pressure fluid flowing through said last named series of radial ports, through said internal groove, said first named series of radial ports and said external groove to one end of the cylinder and through said last named series of radial ports and past said internal flange to the opposite end of the cylinder, and fluid actuated means for throwing said valve into its opposite positions embodying means for supplying pressure fluid to the rear pressure area on the valve and to the rear pressure area on said internal flange, said valve being thrown in one direction by pressure fluid acting on the rear pressure area of the valve at the rear of said external flange and the rear pressure area on said internal flange.
- 80 13. In a pressure fluid motor, a cylinder having a bore, a piston reciprocable therein, and fluid distribution means for effecting reciprocation of said piston including a valve chest having a valve chamber, a fluid actuated fluid distributing valve of the sleeve type reciprocable in said valve chamber and having a rear pressure area, said valve having a rearwardly located enlarged external flange and a forwardly projecting sleeve-like body portion, a groove formed externally on the sleeve-like body portion, a groove formed internally within the valve body portion, a series of radial ports in the valve body traversing the valve body for connecting the internal groove with the external groove, an internal flange on the front end of the valve body, a second series of radial ports traversing the valve body adjacent to and at the rear of said internal flange, passage means controlled by the valve for supplying pressure fluid to the opposite ends of the cylinder, the pressure fluid flowing through said last named series of radial ports, through said internal groove, said first named series of radial ports and said external groove to one end of the cylinder.
- 100 11. In a pressure fluid motor, a cylinder having a bore, a piston reciprocable therein, and fluid distribution means for effecting reciprocation of said piston including a valve chest having a valve chamber, a fluid actuated fluid distributing valve of the sleeve type reciprocable in said valve chamber, said valve having a rearwardly located enlarged external flange and a forwardly projecting sleeve-like body portion, a groove formed externally on the sleeve-like body portion, a groove formed internally within the valve body portion, a series of radial ports in the valve body traversing the valve body for connecting the internal groove with the external groove, an internal flange on the front end of the valve body, a second series of radial ports traversing the valve body adjacent to and at the rear of said internal flange, passage means controlled by the valve for supplying pressure fluid to the opposite ends of the cylinder, the pressure fluid flowing through said last named series of radial ports, through said internal groove, said first named series of radial ports and said external groove to one end of the cylinder.

of radial ports traversing the valve body adjacent to and at the rear of said internal flange, passage means controlled by the valve for supplying pressure fluid to the opposite ends of the cylinder, the pressure fluid flowing through said last named series of radial ports, through said internal groove, said first named series of radial ports and said external groove to one end of the cylinder and through said last named series of 5 radial ports and past said internal flange to the opposite end of the cylinder, and fluid actuated means for throwing said valve into its opposite positions embodying means for supplying pressure fluid to the rear pressure area on the valve 10 and to the rear pressure area on said internal flange, said valve being thrown in one direction by pressure fluid acting on the rear pressure area of the valve at the rear of said external flange and the rear pressure area on said internal flange and 15 20 said valve being thrown in the opposite direction by pressure fluid acting on the front pressure area of the valve.

14. In a pressure fluid motor, a cylinder having a bore, a piston reciprocable therein, and 25 fluid distribution means for effecting reciprocation of said piston including a valve chest having a valve chamber, a fluid actuated fluid distributing valve of the sleeve type reciprocable in said valve chamber, said valve having a rearwardly 30 located enlarged external flange and a forwardly projecting sleeve-like body portion, a groove formed externally on the sleeve-like body portion, a groove formed internally within the valve body portion, a series of radial ports in the valve 35 body traversing the valve body for connecting the internal groove with the external groove, an internal flange on the front end of the valve body, a second series of radial ports traversing the valve body adjacent to and at the rear of 40 said internal flange, passage means controlled by the valve for supplying pressure fluid to the opposite ends of the cylinder, the pressure fluid flowing through said last named series of radial ports through said internal groove, said first 45 named series of radial ports and said external groove to one end of the cylinder and through said last named series of radial ports and past said internal flange to the opposite end of the cylinder, and fluid actuated means for throwing 50 said valve into its opposite positions, said valve being thrown in one direction by pressure fluid acting on the rear pressure area of the valve at the rear of said external flange and the rear pressure area on said internal flange and said 55 valve being thrown in the opposite direction by pressure fluid acting on the front pressure area of the valve, said valve throwing means including a passage controlled by the piston for supplying pressure fluid to said rear pressure area at the rear of said external flange.

15. In a pressure fluid motor, a cylinder having a bore, a piston reciprocable therein, and fluid distribution means for effecting reciprocation of said piston including a valve chamber, a fluid actuated fluid distributing valve of the sleeve type reciprocable in said valve chamber, said valve having a rearwardly located enlarged external flange and a forwardly projecting sleeve-like body portion, a groove formed externally on the sleeve-like body portion, a groove formed internally within the valve body portion, a series of radial ports in the valve body traversing the valve body for connecting the internal groove with the external 70 groove, an internal flange on the front end of 75

the valve body, a second series of radial ports traversing the valve body adjacent to and at the rear of said internal flange, passage means controlled by the valve for supplying pressure fluid to the opposite ends of the cylinder, the pressure fluid flowing through said last named series of radial ports through said internal groove, said first named series of radial ports and said external groove to one end of the cylinder and through said last named series of radial ports and past said internal flange to the opposite end of the cylinder, and fluid actuated means for throwing said valve into its opposite positions, said valve being thrown in one direction by pressure fluid acting on the rear pressure area of the valve at the rear of said external flange and the rear pressure area on said internal flange, said valve throwing means including a passage controlled by the piston for supplying pressure fluid to said rear pressure area at the rear of said external flange, and said valve being thrown in the opposite direction by compression pressure built up in the rear end of the cylinder by the piston and acting on the front pressure area of the valve. 10 15 20 25

16. In a pressure fluid motor, a cylinder having a bore, a piston reciprocable therein, said cylinder having an exhaust port covered and uncovered by the piston for exhausting fluid from the opposite ends of said cylinder, and fluid distribution means for effecting reciprocation of said piston including a distributing valve thrown in opposite directions respectively by cylinder pressure and by compression pressure, passages controlled by said valve for supplying pressure fluid to the opposite ends of said cylinder, and means for delaying the effectiveness of the compression throwing pressure including means distinct from said supply passages for discharging pressure effective after exhaust through said exhaust port is interrupted and closed by movement of said valve in response to compression pressure. 30 35 40

17. In a pressure fluid motor, a cylinder having a bore, a piston reciprocable therein, said cylinder having an exhaust port covered and uncovered by the piston for exhausting fluid from the opposite ends of said cylinder, and fluid distribution means for effecting reciprocation of said piston including a distributing valve thrown in opposite directions respectively by cylinder pressure and by compression pressure, passages controlled by said valve for supplying pressure fluid to the opposite ends of said cylinder, and means for delaying the effectiveness of the compression throwing pressure including means distinct from said supply passages for discharging pressure effective after exhaust through said exhaust port is interrupted and closed by movement of said valve in response to compression pressure and including an exhaust passage within said valve. 45 50 55 60

18. In a pressure fluid motor, a cylinder having a bore, a piston reciprocable therein, said cylinder having an exhaust port covered and uncovered by the piston for exhausting fluid from the opposite ends of said cylinder, and fluid distribution means for effecting reciprocation of said piston including a tubular distributing valve thrown in opposite directions respectively by cylinder pressure and by compression pressure, passages controlled by said valve for supplying pressure fluid to the opposite ends of said cylinder, and means for delaying the effectiveness of the compression throwing pressure including 70 75

- means distinct from said supply passages for discharging pressure effective after exhaust through said exhaust port is interrupted and closed by movement of said valve in response to compression pressure and including an exhaust passage within the bore of said valve.
19. In a pressure fluid motor, a cylinder having a bore, a piston reciprocable therein, said cylinder having an exhaust port covered and uncovered by the piston for exhausting fluid from the opposite ends of said cylinder, and fluid distribution means for effecting reciprocation of said piston including a tubular distributing valve thrown in opposite directions respectively by cylinder pressure and by compression pressure, passages controlled by said valve for supplying pressure fluid to the opposite ends of said cylinder, and means for delaying the effectiveness of the compression throwing pressure including means distinct from said supply passages for discharging pressure effective after exhaust through said exhaust port is interrupted and closed by movement of said valve in response to compression pressure and including an exhaust passage within the bore of said valve and a radial passage through said valve.
20. In a pressure fluid motor, a cylinder having a bore, a piston reciprocable therein, said cylinder having an exhaust port covered and uncovered by the piston for exhausting fluid from the opposite ends of said cylinder, and fluid distribution means for effecting reciprocation of said piston including a distributing valve thrown in opposite directions respectively by cylinder pressure and by compression pressure, passages controlled by said valve for supplying pressure fluid to the opposite ends of said cylinder, and means distinct from said supply passages for providing an auxiliary exhaust for both ends of the cylinder after exhaust through the said exhaust port is interrupted.
21. In a pressure fluid motor, a cylinder having a bore, a piston reciprocable therein, and fluid distribution means for effecting reciprocation of said piston including a valve chest having a valve chamber, a fluid actuated fluid distributing valve movably mounted in said valve chamber, and passage means controlled by said valve for supplying pressure fluid from said valve chamber externally of the valve and through said passage means internally past said valve to provide a double fluid flow past said valve to both ends of said cylinder.
22. In a pressure fluid motor, a cylinder having a bore, a piston reciprocable therein, and fluid distribution means for effecting reciprocation of said piston including a valve chest having a valve chamber, a fluid actuated fluid distributing valve of the hollow sleeve type reciprocably mounted in said valve chamber, and passage

means controlled by said valve for supplying pressure fluid from said valve chamber internally and externally past the inner and outer peripheries of said valve to provide a double fluid flow to both ends of said cylinder, said valve embodying means whereby the pressure fluid, upon fluid flow to the cylinder ends, flows always from the exterior of the valve to the interior thereof.

23. In a pressure fluid motor, a cylinder having a bore, a piston reciprocable therein, and fluid distribution means for effecting reciprocation of said piston including a valve chest having a valve chamber, a fluid actuated fluid distributing valve movably mounted in said valve chamber and having a pressure area adapted to be subjected directly to the action of pressure fluid for moving said valve in one direction, and passage means controlled by said valve for supplying pressure fluid to the opposite ends of said cylinder bore and including passage means in said valve for providing a double fluid flow past the external surface of the valve and through said passage means past the internal surface of said valve to the opposite ends of the cylinder bore.

24. In a pressure fluid motor, a cylinder having a bore, a piston reciprocable therein, and fluid distribution means for effecting reciprocation of said piston including a valve chest having a valve chamber, a fluid actuated fluid distributing valve movably mounted in said valve chamber, and passage means controlled by said valve for supplying pressure fluid to the opposite ends of the cylinder bore for providing a double fluid flow past the external and internal surfaces of the valve to either end of the cylinder bore and including common passages in said valve through which pressure fluid flows internally of said valve to both ends of the cylinder bore.

25. In a pressure fluid motor, a cylinder having a bore, a piston reciprocable therein, and fluid distribution means for effecting reciprocation of said piston including a valve chest having a valve chamber, a fluid actuated fluid distributing valve movably mounted in said valve chamber, and passage means controlled by the valve for supplying pressure fluid to the opposite ends of the cylinder bore and including passage means in said valve for providing a double fluid flow past the external and internal surfaces of the valve, said passage means in said valve providing double flow of pressure fluid past the external and internal surfaces of the valve when said valve is in either its position to supply pressure fluid to the front end of the cylinder bore or its position to supply pressure fluid to the rear end of the cylinder bore, said passage means in said valve being common to the flow of pressure fluid internally of the valve to both ends of said cylinder bore.

ELMER G. GARTIN.
